Patented Dec. 18, 1917.

WITNESS:

Wm. D. Bell.

INVENTOR,

Thomas Prescott.
John D. Ward,
ATTORNEY.

UNITED STATES PATENT OFFICE.

THOMAS PRESCOTT, OF PATERSON, NEW JERSEY, ASSIGNOR OF ONE-FOURTH TO JOHN PRESCOTT AND ONE-FOURTH TO JAMES WAYWELL, BOTH OF PATERSON, NEW JERSEY.

WARPING-MACHINE.

1,250,221.

Specification of Letters Patent. Patented Dec. 18, 1917.

Application filed October 11, 1916. Serial No. 124,978.

To all whom it may concern:

Be it known that I, THOMAS PRESCOTT a citizen of the United States, residing at Paterson, in the county of Passaic and State 5 of New Jersey, have invented certain new and useful Improvements in Warping-Machines, of which the following is a specification.

This invention has for its object to provide means for preventing in the warping operation the formation of so-called "stickers", *i. e.*, binding together of two or more threads as the result of their rolling around each other or their fibers becoming snarled 10 together where the warp is condensed down to a band preliminary to depositing it on the reel. Such stickers are very undesirable because when the warp is put in the loom and the threads affected by a sticker approach 15 the lease rods therein they cannot submit freely to the parting action of the lease rods, and so a tension is set up on those threads that is undue, in consequence of which an undesirable blemish or mark appears in the 20 cloth. I accomplish the object in view by contact means to bear against the taut warp near the reel and keep the threads separated. Preferably this contact means has a contact 25 surface impressionable by the several threads of the band of warp, and is also movable with the advancing warp, as by being a belt or apron of some fabric arranged on a suitable roller or other sliding support; but these are not indispensable, as 30 35 40

the lease rods arranged in the carriage between the two reeds. 55

I place on the reed carriage between the condensing reed and the reel what is in effect a platform over which the taut warp band moves on its way to the reel. In the present construction this platform takes the 60 following form:

Secured to the carriage is a pair of brackets *g* in which is journaled the series *h* of horizontal rollers in inclined and preferably arched disposition. Around these rollers extends an endless belt or apron *i*, fairly taut. The rollers and apron are arranged between the reed *e* and reel and so that the taut warp band, *i. e.*, the warp as condensed by the reed *e*, bears upon the belt, which is of suitable width to accommodate such a band, whatever its width. 65 70 75

In the construction herein shown, due to the contact member afforded by the apron being supported by rollers, said member is free to move with the advancing warp band, being carried along by the friction between it and said warp band. It is preferable that said member be composed of some material that is not hard, like metal, for instance, but 80 impressionable by the threads, so that each thread will in a measure, at least, form a certain degree of impression therein; this quality, especially when combined with the movability of said member with the warp, 85 will insure in any case against the threads becoming involved in the production of a sticker, each thread being held to a definite line across said member notwithstanding 90 those influences, such as static electricity and variations in strain on the threads, which have heretofore been troublesome in causing the threads to become connected with each other, or produce stickers. The material of said member to this end may be 95 some woven fabric, for instance, broadcloth, though I have used even thinner fabrics with perfectly satisfactory results; in fact in the warping of certain kinds of material I have found that perfectly satisfactory results can 100

be obtained without the contact means offering a contact surface that is impressionable at all, provided that it takes the form of a platform, that is, presents appreciable surface lengthwise of the warp. 105

The term "warp" herein used is to be

In the accompanying drawing,

Figure 1 is a side elevation of a fragment of a warping machine including my invention;

Fig. 2 is a plan of the attachment which I apply to said machine in furtherance of my invention; and

Fig. 3 is a side elevation of said attachment.

a is the frame and *b* the suitably driven reel, journaled therein, of a warping machine. *c* is the reed carriage, *d* the main and *e* the condensing reed arranged therein, and

understood as limited to warp threads before they are embodied in the cloth by weaving.

Having thus fully described my invention, what I claim is:

- 5 1. Means to advance under tension and wind up a band of warp threads including a reel and means to keep separated the constituent threads of such band consisting of a platform having an approximately flat contact-surface extending toward and at one side thereof close to the reel and held bearing flatwise against the taut band, said surface being impressionable to the threads.
- 10 2. Means to advance under tension and wind up a band of warp threads including a reel and means to keep separated the constituent threads of such band consisting of a platform having an approximately flat contact surface extending at one side thereof
- 15 3. Means to advance under tension and wind up a band of warp threads including a reel and means to keep separated the constituent threads of such band consisting of a platform having an approximately flat contact surface extending at one side thereof

close to the reel and held bearing flatwise 20 against the taut band, said platform including an apron affording said surface and movable with the advancing threads and means to support the apron.

3. Means to advance under tension and 25 wind up a band of warp threads including a reel and means to keep separated the constituent threads of such band consisting of a platform having an approximately flat contact surface extending at one side thereof 30 close to the reel and held bearing flatwise against the taut band, said platform including an apron affording said surface and movable with the advancing threads and an arched series of rollers supporting the 35 apron.

In testimony whereof I affix my signature.
THOMAS PRESCOTT.
